LIFTING JACK

Frank L. Gormley, Brookline, Mass., assignor to
The Buda Company, Harvey, Ill., a corporation
of Illinois

Application December 14, 1937, Serial No. 179,669

18 Claims. (Cl. 254—111)

This invention relates to ratchet lifting jacks and particularly to that class known as automatic lowering jacks and which have two spring controlled pawls one for lifting the load and the other for holding the ram in raised position while the lifting pawl is moving downwardly into position preparatory to another lifting operation.

One of the principal objects of the present invention is to produce a simple and effective device which is adapted to automatically change the direct operation of both the lifting and holding pawls from raising to lowering position or vice versa.

Another object of the invention is to have the jack so designed that the automatic device will be located in plain sight of the operator and so distinctly marked as to indicate the proper direction of movement of the reversing device for raising and lowering of the ram.

A further object of the invention is to construct the jack so that the lifting pawl and holding pawl will be of the same size and interchangeable with each other, thus bringing about considerable reduction in the cost of manufacture and reduce the number of service parts.

And another object of the invention is to construct the jack that three of its sides will have no obstruction thereon to prevent the use of a load lifting chain on either one of the three sides.

These objects are attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents an elevation partly in section of a lifting jack embodying the principles of the present invention, the various parts thereof being in position for lowering the load.

Figure 2 represents a similar elevation partly in section showing the upper end of said lifting jack with the various parts in position for raising the load.

Figure 3 represents an elevation partly in section of the opposite side of said lifting jack.

Figure 4 represents an elevation of the two

pawls of the jack and showing the means for normally moving them about their pivots into contact with the teeth of the rack or ram.

Figure 5 represents a horizontal section of the jack on line 5, 5 on Fig. 3.

Figure 6 represents a horizontal section of the jack on line 6, 6 on Fig. 3.

Figure 7 represents a horizontal section of the jack on line 7, 7 on Fig. 3.

Figure 8 represents the plan of a portion of 10 the upper end of the lifting jack showing the reversing shaft and the locking lever secured thereto in the position assumed when the jack is raising the load.

Figure 9 represents a similar view with the 15 locking lever in the position it assumes when the jack is lowering the load.

Figure 10 is an enlarged section of the reversing mechanism in the position assumed when the load is being lowered.

Figure 11 is a section of the same on line 11, 11 on Fig. 10.

Figure 12 is an elevation of a modified form of the yielding member adapted to connect the projections on the two pivoted pawls when the load 25 is being lowered, and

Figure 13 represents a side elevation of the same.

Similar characters indicate like parts throughout the several figures of the drawings.

In the drawings, 10 is the base of the jack and this base has extending upwardly therefrom a hollow casing 11, from the upper end of which projects a handle 12 by which the jack may be carried from place to place.

As shown at 11x the casing 11 is open at the front to give access to the operating mechanism.

This casing 11 is provided at the top with a square bearing 13 through which extends the 40 rectangular ram or rack 14, this rack having on the front side thereof a plurality of teeth 15.

The ram or rack 14 has secured to its upper end a supporting head 16 and at its lower end has formed integral therewith and projecting 45 rearwardly therefrom another supporting member 17. Either the head 16 or the projection 17 may be used to support a load.

The projecting member 17 extends through a slot 18 in the rear wall 19 of the casing 11.

The lower rear face of the ram 14 contacts with the lower inner face of this wall 19 as it reciprocates endwise therein, the teeth 15 of said ram being free from contact with the opposite wall 20 of said casing 11.

Ribs 10x contact with the opposite side walls of the ram 14 and prevent any lateral movement of the same during its endwise movement.

The ram 14 may be inserted through an opening 21 in the base 10 and after such insertion the head 16 is secured to the upper end of the ram by means of the pin 22.

The opposite side walls of the casing 11 have openings therein to receive the oppositely disposed cup-shaped members 23 held in the side walls of the casing 11 by set screws 23x.

Disposed within these cup-shaped members 23 are trunnions 24 projecting from the opposite sides of a member 25 provided with sockets 25x either of which is adapted to receive an actuating lever 251 whereby said member 25 may be moved in either direction about the axis of said trunnions 24.

The walls of the casing 11 are so constructed that the trunnions 24 may be moved into position so that the cup-shaped members 23 may be disposed over the ends thereof and form bearings therefor.

The inner end of the socketed member 25 is provided with a semi-cylindrical seat 26 to receive the cylindrical hub 27 of a lifting pawl 28 and one wall of said inner end is cut away as at 28x to permit the insertion of the pawl 28 from one side of the socketed member 25 with its cylindrical hub 27 disposed in the seat 26.

The wall on the opposite side of the socketed member 25 is provided with a cylindrical bearing 27x to receive one end of the hub 27.

The pawl 28 is adapted to oscillate about the axis of hub 27 and at its upper end is provided with a plurality of teeth 29 adapted to engage the teeth 15 of the ram or rack 14.

Near the upper end of the casing 11 and integral therewith is a concaved seat 30 closed at one end by plate 30x.

Extending inwardly from the opposite end of said seat is a tubular member 31, a portion of the wall of which is cut away to permit the oscillation therein of the hub 31x of the holding pawl 32, the upper end of which has formed thereon a plurality of teeth 33 adapted to engage the teeth 15 of the ram or rack 14 and prevent the accidental lowering of the ram or rack 14.

The member 31 is held in position by means of a set screw 301.

To one side wall of the casing 11 is secured a headed stud 39 about which is coiled a spring 40.

One end of this spring 40 coacts with a side extension 41 formed upon the lifting pawl 28 while the opposite end of said spring coacts with a similar projection 41x on one side of the holding pawl 32, the tension of said spring 40 being such as to cause the ends thereof to spring away from each other.

The same spring 40 therefore tends, under normal conditions, to force the teeth of both of the pawls 28 and 32 into engagement with the teeth 15 of the ram or rack 14.

The socketed member 25 is provided with a downward projection 42 which is adapted to engage the shoulder 43 on the casing 11 to limit the downward movement of said member, and another shoulder 43x on the casing 11 limits the upward movement of said member 25.

The two sockets 25x are provided in order that different leverages may be obtained in the operation of the jack under varying conditions.

When the member 25 is moved downwardly under certain conditions the lifting pawl will raise the ram or rack 14, the holding pawl 32 being

forced outwardly from engagement with the rack teeth 15 against the tension of the spring 40, while the rack teeth 15 are passing the teeth 33 of said holding pawl 32.

As soon as the member 25 has reached the end of any of its downward movements, the spring 40 will force the teeth 33 of the holding pawl 32 into engagement with the rack teeth 15 and retain the rack 14 in position while the pawl 28 is being moved downwardly into a lower position preparatory to another lifting operation.

This is of considerable importance as with this type of jack there has always been a tendency for the holding and lifting pawls 28, 32 to fly out of contact with the rack teeth 15 and allow said rack 14 and the load supported thereby to accidentally lower and thus cause serious accidents.

By providing a single spring 40 in the manner shown and described both of the pawls 28, 32 at all times are retained in position to engage with the rack teeth 15 when, in the operation of the jack, it is necessary for the teeth of either pawl 28, 32 to engage the teeth 15 of the ram 14.

The lifting pawl 28 and the holding pawl 32 are exactly alike and either one may be used in place of the other. This reduces the cost of manufacture to some extent.

The lifting pawl 28 and the holding pawl 32 are both fulcrumed at their lower ends and extend upwardly from said fulcrums with the teeth 29 and 33 at the upper ends thereof.

The pawls 28 and 32 have arms 44, 45 extending rearwardly from one side thereof.

The arm 44 on the lifting pawl 28 has a lateral trunnion or projection 46 on which is mounted an annular member 47 having a radial extension 48, the periphery of which is grooved to receive one end of a yielding helical spring 49.

The opposite end of this spring 49 is coiled about a helical groove in the periphery of an extension 50 forming a part of and extending downwardly from a U-shaped block 51 having a flat sided notch 51x therein, said block 51 being provided with a slotted upward extension 52 which encloses a reversing shaft 53.

The arm 45 on pawl 32 is provided with a lateral trunnion or projection 45x which is adapted to be disposed in the notch 51x when a load is being lowered.

The shaft 53 is rotatable in an elongated bearing 54 formed in the casing 11 and has secured to the outer end thereof an actuating wing or lever 55 by which said shaft 53 may be rotated part way about its axis and also under certain conditions moved forwardly and then locked in its forward position by means to be described hereinafter.

The opposite or rear end of the reversing shaft 53 has a collar 56 secured thereto between which and the slotted extension 52 is a helical buffer spring 56x and between the rear end of the bearing 54 and the slotted extension 52 is a longer expandable spring 57 coiled about the reversing shaft 53, said spring 57 being adapted to be expanded during the lowering of the load.

When raising the load by the oscillation of the socketed member 25 with the teeth 29 of the pawl 28 in engagement with the teeth 15 of the rack or ram 14, the spring 57 will be under compression and the wing 55 locked from turning, the slotted extension 52 at this time freely reciprocating vertically while enclosing the reversing shaft 53 without performing any operation.

When it is desired to reverse the movements of the lifting pawl 28 and holding pawl 32 pre-

paratory to lowering the load, the operator seizes the wing 55 while in locked position and gives the reversing shaft 53 a quarter turn to the right thereby moving the cam member 55x thereon from engagement with the inclined locking notch 551.

When thus unlocked the spring 57 is free to expand and its expansion will move the shaft 53 to the rear and at the same time said expansion of said spring acting on the slotted end 52 will move the yielding member 49 into the position shown in Fig. 1 with the projection 45x disposed in the notch 51x, thus causing the pawls 28, 32 to be yieldingly connected together.

15 When the cam member 55x of the wing 55 is engaged with shoulder 551 the reversing shaft 53 will be prevented from any movement in a rearward direction and the spring will be kept under compression until released.

20 When in the operation of the jack it is desired to lower the load, the spring 57 is permitted to expand and cause the extension 45x on the holding pawl 32 to enter the notch 51x in block 51, the spring 57 under expansion causing the spring 25 49 and its associated parts to move about its fulcrum 46 so that the extension 45x will be retained in the notch 51x of the U-shaped block 51 during the lowering of the load.

When this has been accomplished it is obvious 30 that the lifting pawl 28 and the holding pawl 32 will be connected together through the expansible spring 49 and the elements connected thereto, thereby permitting these pawls to operate alternately as holding pawls.

35 When the load is being raised the reversing spring 49 will be in the position indicated in Fig. 2 of the drawings, the lower end of said spring being connected to the projection 46 on the lifting pawl 28.

40 This reversing spring 49 is movable with the lifting pawl 28 and when a load is being raised floats freely in an upward and downward direction, the upper end thereof moving transversely of and being guided by the reversing shaft 53.

45 At this time the projection 45x of pawl 32 will be disconnected from the U-shaped block 51 and the pawls 28, 32 will be disconnected from each other.

When it is desired to lower the load the reversing shaft wing 55 on the front side of jack is 50 placed in position to permit the movement of the shaft 53 to the rear into the position shown in Fig. 1.

This rearward movement will be effected by the 55 expansion of the spring 57, which in its expansion will force the yielding reversing spring 49 into position to connect together both pawls 28, 32 preparatory to lowering the load.

The diameter of the projection 45x is somewhat 60 less than the width of notch 51x so that there is some lost motion between the two.

On the upward stroke of the socketed member 25 the reversing spring 49 will be drawn downward and the surface A of the notch 51x in the 65 U-shaped block 51 connected to the reversing spring 49 will come in contact with the projection 45x of the holding pawl 32.

The upward stroke of the socketed member 25 will then continue until sufficient tension has been placed on the reversing spring 49 to disengage the lifting pawl 28 from teeth 15 in the rack bar 14.

The socketed member 25 will then be operated in a downward direction and while being operated in this direction the reversing spring 49 will be 70 raised and the surface C of the U-shaped block

51 will come into contact with the lower side of the projection 45x on the holding pawl 32.

This downward stroke of the socketed member 25 will continue until sufficient tension has been placed on the reversing spring 49 to disengage the holding pawl 32 from the teeth 15 in the rack bar 14.

After the holding pawl 32 has been released from the teeth 15 in the rack bar 14, the socketed member 25 will be operated in the upward direction, thus allowing the load to lower until the holding pawl 32 contacts with another tooth in the rack bar 14.

The lowering of the load in this manner may continue so long as the reversing shaft wing 55 is in its unlocked position and the socketed member 25 is operated in an upward and downward direction.

In lifting jacks of this character two pawls are always utilized, one being a lifting pawl 28 to 20 raise a load, while the other such as 32 is the holding pawl to hold the load during the raising operation.

In the present device when lowering the load the operation of the pawl 28 may be reversed so 25 that it may act as a holding pawl while the pawl 32 is being moved into a new position preparatory to a further engagement with the teeth 15 of ram 14.

In the present device the pawl 28 known as the 30 lifting pawl is connected to and operated by the socketed member 25 fulcrumed on the main jack frame or casing while the fulcrum of the other pawl 32 or holding pawl is mounted in a tubular member 31 disposed on a seat 30 which is a part 35 of said main frame or casing.

When the jack is used to raise a load the lifting pawl 28 is operated by the socketed member 25 and will raise the rack bar 14 a certain distance, this distance depending on how much off 40 center the fulcrum 27 of the lifting pawl 28 is located from the fulcrum center 23 of the socketed member 25.

The rack bar 14 is raised in this manner so that the teeth 15 will pass over the teeth 33 of 45 the holding pawl 32.

This holding pawl 32 will hold the load while another upward stroke of the socketed member 25 is being made, preparatory to further lifting of the load.

When the load is to be lowered the reversing lever 55 is turned clockwise to disengage the cam member 55x from the locking notch 551 so that the lifting pawl 28 and holding pawl 32 will be connected together and the operation of the lifting pawl 28 will be reversed, said pawl 28 acting as an additional holding pawl while the load is being lowered.

Obviously, it is quite necessary for the lifting pawl 28 to move upward clear of the rack teeth 15 60 while the holding pawl 32 supports the load.

Near the end of its upward travel the lifting pawl 28 will engage the rack teeth 15 and raise the rack 14 sufficiently to release the load from 65 the holding pawl 32.

The holding pawl 32 will then move clear of the rack teeth and allow the load to be lowered while supported by the lifting pawl 28, which is being moved by the socketed member 25.

The holding pawl 28 will come into proper position to hold the load when the required distance downwardly of the rack 14 has been reached in the lowering operation.

This operation may be repeated by operating 75

the socketed member 25 until the load has been lowered the required distance.

After this has been accomplished, by turning the reversing lever 55 into its locked position with spring 57 compressed and then operating the socketed member 25 as previously stated, the pawls 28 and 32 will be disconnected and operate in the usual manner to raise the load.

The casing has an opening 58 extending therethrough to form a handle by which the jack may be moved from place to place.

When the two pawls 28 and 32 have been connected in the manner described, the load may be automatically lowered.

15 In the present jack the control for reversing the operation of the pawls is located at the front of the jack where it can be plainly seen and this control is also plainly marked so that the operator can tell in just what direction the ram 14 will operate either in raising or lowering a load, thereby avoiding accidents in operating.

It will be noted that in the present device the load may be raised or lowered on three sides of the jack by using chain lifts if necessary without any obstruction from the side of the jack to prevent the raising or lowering of the load.

In lifting by chains the links of the chains are disposed in the slots 60 of head 16.

The casing 11 is provided on one side with an arcuate flange 61 partially surrounding the lever or wing 55 and preventing it from being moved accidentally.

30 The spring 49, block 51 and member 47 form a yielding connection between the pawls 28 and 32 during the lowering of the load.

If desired, the yielding connection may be made of a single wire 62 of spring steel as shown in Figs. 12 and 13.

This modified form of yielding connection has 40 at its lower end a loop 47x through which the projection 46 of pawl 28 extends and near its upper end is bent U-shaped as at 50x to form a notch 41x to receive the projection 45x of the holding pawl 32.

45 Between the loop 47x and notch 51x the wire 62 has coils 49x therein forming a yielding spring connection between said loop 47x and notched portion 40x.

Above the notched portion 40x the wire 62 extends upwardly and downwardly over the reversing shaft 53 as indicated at 52x.

This upward extension 52x straddles the shaft 53 and is movable transversely thereof between the springs 56x and 57.

55 Opposite the yielding member 49 or 62, the casing 11 has an opening 63 in one wall thereof normally closed by a plate 63x which may be removed to give access to said yielding member.

It is believed that the operation and many advantages of the invention will be understood without further description.

Having thus described my invention, I claim:

1. A ratchet lifting jack consisting of a vertically movable rack having a plurality of rack teeth; a lifting pawl; a holding pawl; means for oscillating said lifting pawl; a yielding member supported on said lifting pawl and movable therewith; and means for connecting the upper end of said yielding member to the holding pawl preparatory to the lowering of the load.

2. A lifting jack as set forth in claim 1 in which the lifting pawl and the holding pawl are alike and interchangeable.

3. A lifting jack as set forth in claim 1 in 75 which said yielding member includes a U-shaped

block; a projection on the holding pawl adapted to coact with said U-shaped block; and means for retaining said projection in the notch of said block during the lowering of the load.

4. A lifting jack as set forth in claim 1 in 5 which said yielding member includes a U-shaped block; a projection on said holding pawl adapted to coact with said U-shaped block; and spring controlled mechanism for retaining said projection in the notch of said block during the lower- 10 ing of the load.

5. A lifting jack as set forth in claim 1 in which the yielding member is formed of a single wire having a loop at one end adapted to coact with the lifting pawl, a notch to coact with a 15 projection on the holding pawl, and coils under spring tension between said notch and loop.

6. A lifting jack as set forth in claim 1 in which said yielding member includes a notched block; a projection on the holding pawl adapted to 20 coact with the notch of said block but disengaged therefrom during the lifting operation; and means for forcing said projection into the notch of said block and retaining it therein during the lowering of the load.

25 7. A lifting jack as set forth in claim 1 in which said yielding member includes a coiled spring and a notched block mounted on the upper end of said spring and having a slotted upper end; a projection on said holding pawl 30 adapted to be forced into the notch of said block but disengaged therefrom during the lifting operation; a reversing shaft extending through said slot; and spring controlled mechanism coacting with said shaft for forcing said projection into 35 the notch of said block and retaining it therein during the lowering of the load.

8. A lifting jack as set forth in claim 1 in which said yielding member includes a coiled spring and a notched block mounted on the upper end of said spring and having a slotted upper end; a projection on said holding pawl adapted to be forced into the notch of said block but disengaged therefrom during the lifting operation; a reversing shaft extending through said slot; an 40 expandable spring surrounding said shaft and bearing against said slotted end; means for retaining said spring under compression during the lifting operation; and means for releasing said spring and retaining it expanded during the low- 45 ering of the load.

9. A lifting jack as set forth in claim 1 in which said yielding member includes a coiled spring and a notched block mounted on the upper end of said spring and having a slotted upper end; a projection on said holding pawl adapted to be forced into the notch of said block but disengaged therefrom during the lifting operation; an oscillatory reversing shaft extending through said slot; an expandable spring surrounding said shaft and bearing against one side of said slotted end; means at one end of said shaft for moving it forward and locking it in adjusted position; and means on the opposite end of said shaft and bearing against said forked end 60 adapted to compress said spring during the forward movement of the shaft.

10. A lifting jack as set forth in claim 1 in which said yielding member includes a coiled spring and a notched block mounted on the upper 70 end of said spring and having a slotted upper end; a projection on said holding pawl adapted to be forced into the notch of said block but disengaged therefrom during the lifting operation; an oscillatory and reciprocable reversing shaft extend- 75

ing through said fork; an expansible spring surrounding said shaft and bearing against one side of said slotted end; a collar secured to the rear end of said shaft; a buffer spring between said collar and the opposite side of said slotted end; and a cam lever on the forward end of said shaft for moving it forward to compress the spring during the lifting operation and to subsequently release said spring permitting it to expand and force the projection of the holding pawl into the notch of said block and retain it in engagement therewith during the lowering of the load.

11. A ratchet lifting jack consisting of a vertically movable rack having a plurality of rack teeth; a lifting pawl; a holding pawl; a projection on the side of each pawl; means for oscillating said lifting pawl; a yielding member pivotally mounted on the projection of the lifting pawl and movable therewith and provided with a notch near its upper end to receive the projection of the holding pawl thereby providing a connection between said pawls and causing them to alternately engage the rack teeth during the lowering of the load; and means for controlling the engagement and disengagement of said projection with the notch of said yielding member.

12. A lifting jack as set forth in claim 11 in which the projection on the holding pawl has a diameter slightly less than the width of said notch.

13. A ratchet lifting jack consisting of a vertically movable rack having a plurality of rack teeth; a lifting pawl; a holding pawl; a projection on the side of each pawl; means for oscillating said lifting pawl; a yielding member pivotally mounted on the projection of the lifting pawl and movable therewith, said yielding member having near its upper end a notch with parallel sides adapted to receive the projection on said holding pawl; and means for retaining said

holding-pawl projection in said notch during the lowering of the load.

14. A lifting jack as set forth in claim 13 in which the means for retaining said holding-pawl projection in said notch includes an expansible spring.

15. A lifting jack as set forth in claim 13 in which an expansible spring is provided to force said holding-pawl projection into said notch and retain it in said notch during the lowering of the load; and means for locking said spring under compression during the lifting of the load.

16. A lifting jack as set forth in claim 13 in which said yielding member has a slotted upper end; a projection on said holding pawl adapted to be forced into said notch but is disengaged therefrom during the lifting operation; a reversing shaft extending through said fork; and spring controlled mechanism on said shaft for forcing said holding-pawl projection into the notch of said block and retaining it in engagement therewith during the lowering of the load.

17. A ratchet lifting jack consisting of a vertically movable rack having a plurality of rack teeth; a lifting pawl; a holding pawl; a projection on the side of each pawl; means for oscillating said lifting pawl; a yielding member supported on said lifting pawl and during the lifting operation movable therewith independently of the holding pawl; and reversing means operable to connect the upper end of said yielding member with the projection of the holding pawl during the lowering of the load.

18. A ratchet lifting jack as set forth in claim 17, in which a casing enclosing said mechanism has three flat sides free from obstruction whereby a lifting chain supported by the head of said rack may be used on either of said sides.

FRANK L. GORMLEY.
